(57) CLAIM

The ornamental design for a water bottle holder with belt clip, as shown and described.

DESCRIPTION

FIG. 1 is a front right perspective view of a water bottle holder with belt clip showing our new design in use with environment;

FIG. 2 is a front right perspective view of a water bottle holder with belt clip;

FIG. 3 is a rear right perspective view thereof;

FIG. 4 is a bottom front perspective view thereof;

FIG. 5 is a front side view thereof;

FIG. 6 is a right side view, the left side being a mirror image thereof;

FIG. 7 is a rear side view thereof; and

FIG. 8 is a top plan view thereof; and,

FIG. 9 is a bottom plan view thereof.

The broken lines depict portions of the article and environment that form no part of the claimed design.

1 Claim, 9 Drawing Sheets
